UNITED STATES PATENT OFFICE

2,672,035

SINKER HEAD FOR FLAT FULL-FASHIONED
KNITTING MACHINES

John J. Slattery, Merchantville, N. J.

Application August 14, 1952, Serial No. 304,391

3 Claims. (Cl. 66—98)

1

The present invention relates to flat full fashioned knitting machines and is concerned primarily with certain improvements in the press edge of the sinker head bottom which are designed to eliminate breakage of the beards of the needles which engage thereagainst.

A full fashioned knitting machine includes a sinker head having a bottom that is formed with a plurality of transverse slots each of which accommodates either a sinker or a divider that reciprocates therein. These slots extend through the press edge of the sinker head bottom and define or mark off lands. During the ordinary operation of the full fashioned knitting machines, the beards of the needles engage these lands on the press edge and due to this engagement, are closed over the yarn.

Each needle has a beard formed with a point that is inclined back towards the shank of the needle and this inclined point is intended to engage the upper beveled edge of the press edge to start the closing action. However, in actual practice the engagement is not always what it should be and in many instances the beards of the needles are deformed and break off and in other cases the beards are not properly centered or aligned with respect to the shanks. The present invention has in view as its foremost objective the elimination of this breakage of the beards of the needles and a definite assurance that the beards will be properly centered.

An important object of the invention is to provide, in a flat full fashioned knitting machine, a sinker head bottom having a press edge that is divided into lands by transverse slots with means for guiding the beards of the needles so that these beards are gradually aligned with the needles on downward motion of the latter.

More in detail the invention has as an object the provision, in a sinker head bottom of a flat full fashioned knitting machine of a vertically arranged V-shaped groove of gradually diminishing cross-section that is located in each land substantially midway between the slots that define that land. Each of these V-shaped grooves has a wide open mouth that is located in the upper beveled edge of the press edge with a cross-section gradually diminishing to a point that is spaced from the bottom of the press edge. When the point of the beard first enters this V-shaped slot, it engages one side or the other of the slot and as downward motion of the needle takes place, it is gradually aligned with the needle so that when it reaches the press edge proper, it is accurately positioned for closing over the yarn.

2

Another important advantage afforded by these grooves is that they are a great aid to an operator in setting up needles in the needle bar. The grooves serve as a guide for the workman in centering the beards.

Various other more detailed objects and advantages of the invention such as arise in connection with carrying out the above noted ideas in a practical improvement will in part become apparent and in part be hereinafter stated as the description of the invention proceeds.

The invention therefore comprises a sinker head bottom of a flat full fashioned knitting machine having a press edge that is divided into lands by transverse slots with each land of the press edge being formed with a V-shaped groove of gradually diminishing cross-section, having an open mouth that opens onto the upper beveled edge immediately above the press edge.

For a full and more complete understanding of the invention, reference may be had to the following description and accompanying drawing wherein:

Figure 1 is a view taken as a transverse vertical section through the sinker head of a flat full fashioned knitting machine, and illustrating the point of the beard of a needle as it is about to engage the press edge which includes the improvements of this invention.

Figure 2 is a sectional view similar to Figure 1 illustrating the relative position of the needle after the beard has been closed.

Figure 3 is a view in front elevation of a portion of the sinker head bottom; and

Figure 4 is a top plan view of that portion of the sinker head bottom illustrated in Figure 3.

Referring now to the drawing, wherein like reference characters denote corresponding parts and first more particularly to Figures 1 and 2, a knitting needle of the spring beard type is therein illustrated and referred to in its entirety by the reference character N. These needles N are typical of those which are commonly used in a flat full fashioned knitting machine. Each needle N comprises a shank 10 which terminates at its upper end at a hook 11, to which is integrally joined a spring beard 12 having a point 13 that is defined by crimp 14. It will be noted that the point 13 is slightly inclined back towards the shank 10. In the open position of the needle, there is a yarn space at 15, but this space is closed upon completion of the downward stroke of the needle as illustrated in Figure 2.

The flat full fashioned knitting machine includes a sinker head, which is referred to in its

entirety by the reference character H. The sinker head H comprises a cap or top 16, and a bottom 17. The bottom 17 is formed with a plurality of transverse vertical slots 18. The sinker head bottom 17 also has an exposed edge surface at 17, which is known as the press edge. Immediately above this press edge 19 there is a beveled edge 20. The slots 18 are carried through this beveled edge 20 and also through the press edge 19; although they do not reach the bottom of the latter as illustrated in Figure 3.

These slots 18 mark off or define in the press edge 19 a plurality of lands 21, thus, there is a slot 18 on each side of each land 21.

Formed in each land 21 is a vertically arranged V-shaped groove of gradually diminishing cross-section. Each of these grooves is referred to in its entirety by the reference character G. Each groove G is made up of a pair of inclined side walls 22 and 23 which meet at the bottom at an apex 24 with the side walls coming together at a point 25, which it will be noted is spaced at an appreciable distance above the bottom of the press edge 19. Each groove G also includes upper inclined edges 26 and 27, which are located on the beveled edge 20. Thus, each groove G has an open mouth that is located in the beveled edge 20, and has a V-shaped cross-section which gradually diminishes to the point 25.

While the manner in which one of these grooves G functions as a guide for the beard point 13 of one of the needles N is believed to be obvious from the illustration of the drawing and description of parts given, it may be briefly outlined as follows:

Upon referring to Figure 1, it will be noted that as a needle N begins its downward stroke, the beard point 13 will enter the wide open mouth of the groove G. It may be assumed that this beard point 13 is not at this stage in accurate alignment with the shank 10. Thus, it will engage one of the surfaces 22 or 23 of the groove. As downward movement is continued, the incline of the surface with which the beard point engages will gradually bring the beard point into alignment with the shank 10 of the needle. Thus, when the beard point reaches the press edge 19 proper, it will be accurately aligned with the shank of the needle and will close over the yarn and assume the position depicted in Figure 2.

While a preferred specific embodiment of the invention is herein set forth, it is to be clearly understood that the invention is not to be limited to the exact construction and design of the grooves because various modifications of these details may be provided in putting the invention into practice within the purview of the appended claims.

What is claimed is:

10. 1. In a flat full fashioned knitting machine, including a sinker head having a bottom formed with a press edge, said press edge being provided with a plurality of vertically arranged V-shaped grooves of gradually diminishing cross-section with the widest part of each groove being upwardly disposed.
20. 2. In a flat full fashioned knitting machine, including a sinker head having a bottom formed with a press edge, a beveled edge over said press edge and a plurality of vertical transverse slots defining lands on said press edge, the improvement consisting of a vertically arranged V-shaped groove of gradually diminishing cross-section formed in each of said lands with the widest part of each groove opening into said beveled edge.
30. 3. In a flat full fashioned knitting machine, including a sinker head having a bottom formed with a press edge, a beveled edge over said press edge and a plurality of vertical transverse slots defining lands on said press edge, the improvement consisting of a vertically arranged V-shaped groove of gradually diminishing cross-section formed in each of said lands, each of said grooves being defined by inclined side surfaces which meet at an apex which terminates at a point in the face of the land spaced from the bottom thereof, with each of said surfaces having an upper edge located in said beveled edge.

JOHN J. SLATTERY.
